UNITED STATES PATENT OFFICE.

ERNEST LOESSER, OF GLEN RIDGE, NEW JERSEY, ASSIGNOR, BY DIRECT AND MESNE ASSIGNMENTS, TO NEW DIAMOND POLISHING TOOL COMPANY OF AMERICA, INC., OF NEW YORK, N. Y., A CORPORATION OF NEW YORK.

APPARATUS FOR GRINDING AND POLISHING PRECIOUS STONES.

1,094,913.

Specification of Letters Patent. Patented Apr. 28, 1914.

Application filed June 1, 1910. Serial No. 564,347.

To all whom it may concern:

Be it known that I, ERNEST LOESSER, a citizen of the United States of America, residing in Glen Ridge, county of Essex, and 5 State of New Jersey, have invented a certain Improved Apparatus for Grinding and Polishing Precious Stones, of which the following is a specification.

This invention comprises a new organization wherein a rotatable dop is mounted so that it may be readily turned through known definite increments of rotation so that successive facets may be ground or polished, when the axis of the dop is disposed at a 10 given angle to the surface of the grinding or polishing lap. The dop may be adjusted by mere rotation about its axis for the grinding or polishing of successive facets of the same series. Thus, having reference 15 to the top of the stone, all of the "corner and bezels" facets may be successively ground after which the angle of the axis of the dop may be changed so that the next series or "star" facets may be successively 20 cut, following which the angle of the axis may be again changed to cut the successive facets known as "haves". The table may be ground when the axis of the dop is vertical. In like manner, the collets and facets 25 30 below the girdle may be ground.

The dop holder may be so constructed as to have the capacity of angular adjustment. It is preferred, however, that the dop shall be rotatably mounted in one holder for cutting one series of facets and that then it be transferred to another holder disposed at a different angle in which it may be rotated for cutting successively the facets of another series, and so on. These holders of 35 40 different angular relation to the plane of the face of the lap may be removably connected with the same apparatus. In practice, however, it is preferred that there shall be a series of apparatus one for each angle 45 at which the various series of facets are ground, and that the dop, when one series of facets has been ground, shall be transferred to another apparatus. This plan is thought to have advantages over the use of 50 a single apparatus having the capacity for angular adjustment of the dop holder.

In the accompanying drawings Figure 1 is a side elevation: Fig. 2, a plan view: Fig.

3, a vertical sectional view through the dop holder: Fig. 4, a detail side elevation of the 55 dop holder with its axis at a different angle from that shown in Fig. 3: Fig. 5, a detail plan view looking down upon the top of the dop: Fig. 6 showing the dop removed from the apparatus.

1 indicates a horizontal bed plate. Appropriately supported upon it stands the supporting frame 2 of the dop holder. This frame has at the rear two posts or feet 3 that seat upon the table 1. On the table, 60 suitably adjacent the outer end of the frame of the dop holder is a post 4 having an adjustable head so that the workman may with certainty adjust the frame 2 so that it shall be exactly horizontal when the grinding of 65 a facet has been completed. The frame 2 is held against lateral displacement in the usual way by posts 5, 5 fixed in the bed plate. The outer end of frame 2 is formed with a head 6 having a bore at right angles 70 to the surface of the bed 1 and, of course, also to the grinding or polishing surface of the rotating lap 7. This bore is formed with a key way to receive a key 8 on a sleeve fitting within the bore and having applied to 75 it above and below the head nuts 9, 9, so that the position of the sleeve within the head may be adjusted as desired. Within the sleeve, which has a tapered or flared opening top and bottom, is fitted a spindle 80 85 10 having a tapered shoulder 11 and to the upper end of the sleeve is applied a tapered washer over which lies a nut 12 screwing on the end of the spindle. The spindle may therefore be held rigidly within the sleeve at the desired elevation or may be held frictionally therein so as to resist the ordinary stress of the grinding or polishing operation and yet be capable of being forcibly turned by hand. The lower end of the spindle 10 carries a head 13 disposed at an angle to the axis of the spindle and having in it a conical seat open at the top and bottom the axis of which is, as in Figs. 1 and 3, disposed at an angle of forty five degrees to the axis of 90 the spindle. This head will be called the dop holder. Seated in it so as to turn therein is a correspondingly shaped dop 14 in the apex end of which is secured the stone 15 to be operated upon and at the larger end of 105 which is a toothed wheel 16. In an offset

- 17 of the head 13 is mounted to turn a bolt having an arm 18 projecting at right angles and having a tapped aperture that may be brought to a position concentric to the axis 5 of the dop seat in the holder. When the arm 18 is thrown to one side, the dop 14 may be dropped into the holder and then suitably held therein by the adjustable threaded bolt 19 working in the threaded aperture in the arm 18. Secured to the holder 13 is a leaf spring 20 having a tooth at its end that engages the teeth of the toothed or ratchet wheel 16.
- With the parts disposed as in Figs. 1 and 15, the rapidly revolving lap will grind or polish a facet of the stone and when the desired plane of the facet has been reached, the frame 2 will come in contact with post 4 and no further abrasion of the facet can 20 occur, however long the dop may remain in the position in relation to the rapidly revolving lap. To grind the next facet of the same series an increment of rotation is given to the dop within its holder, the screw 19 25 may be loosened, the spring 20 withdrawn from the ratchet wheel and the dop turned through any number of arcs equal to one or any desired number of the teeth 16 when the spring is permitted to reengage the wheel 30 and the screw bolt 19 may again be tightened. When all the facets of a given series have been ground, the dop holder, being in such case appropriately constructed thereto, may be adjusted to a different angle,—for 35 instance to the angle required for cutting of the next series of facets or the dop may be removed from the holder and transferred to that of another grinding apparatus in which the axis of the holder is at the desired 40 angle. When the top or bottom of the stone has been ground with the desired facets, the stone may be re-set in another dop with the other side downward and then in the same manner the facets for that side are ground.
- 45 If the axis of the dop holder be perpendicular to the face of the lap, then, of course, the table or collet (as the case may be) may be ground.
- Experience has demonstrated that the 50 general organization depicted in the drawing is efficient and it is, of course, characterized by great simplicity. Nevertheless, changes may be made by those skilled in the art without departing from the spirit of 55 this invention.
- It will be seen from Fig. 3, that the stone in the dop is in line, or substantially so, with the axis of the vertical spindle 10, which is rotatively adjustable.
- 60 This method of grinding is applicable not only to the brilliant cut, and also of course to the rose cut, but to the step cut of square or oblong stones.
- I claim:
- 65 1. Precious stone grinding apparatus comprising a dop holder having a conical socket open at both ends, the larger end of which is uppermost to receive a correspondingly shaped dop having a stone held in the apex thereof and means for holding the dop 70 within the socket.
2. Precious stone grinding apparatus comprising a dop holder having a conical socket open at both ends, the larger end of which is uppermost and whose axis is disposed at 75 an angle to the plane in which the surface of the grinding lap runs, a correspondingly shaped dop seated and held in said socket and means by which the dop may at will be rotated through measured determined distances whereby facets of a series may be successively cut.
3. Apparatus for grinding precious stones comprising a dop holder having a conical dop seat open at both ends, the larger end of which is uppermost and with its axis disposed at an angle to the plane in which the surface of the grinding lap runs, a dop seated therein and carrying at its apex 85 end the stone to be operated upon and having at its head a toothed wheel and means for engaging the wheel to hold it successively in adjustable positions whereby facets of a series may be successively cut.
4. Precious stone grinding apparatus comprising a dop holder having a conical dop seat whose axis is at an angle to the plane in which the surface of the lap runs, a dop seated therein and carrying the stone to be operated upon at the apex end of the dop 90 and in line with its axis and means whereby the dop may be turned about its axis through determined measured arcs.
5. Precious stone grinding apparatus comprising a dop holder having a conical dop seat open at both ends, the larger end of which is uppermost, a swinging arm having a dop holding screw therein and a detent device adapted to engage a dop seated in the seat to determine its adjustment therein.
6. Apparatus for grinding precious stones, comprising a vertical spindle, a dop holder carried thereby in a fixed relation thereto and having in it a dop-seat whose axis is at an angle to the axis of the spindle and which is adapted to receive a dop inserted through the top thereof, a dop seated in said seat with the end thereof in line with the axis of said spindle, or substantially so, and adapted to be progressively adjusted by rotation in said seat without removal therefrom, and means for locking the dop in adjusted positions, whereby all the facets of a series may be progressively ground.
7. Apparatus for grinding precious stones, comprising a vertical spindle, a dop holder carried thereby in a fixed relation thereto and having in it a dop-seat whose axis is at an angle to the axis of the spindle, a dop seated in said seat with the end thereof 125
- 130

in line with the axis of said spindle, or substantially so, and adapted to be progressively adjusted by rotation in said seat without removal therefrom, and means for locking the dop in adjusted positions, whereby all the facets of a series may be progressively ground.

In testimony whereof, I have hereunto subscribed my name.
